ELECTRON TUBE

Fritz Michelssen, Berlin, Germany, assignor to
 Telefunken Gesellschaft fur Drahtlose Tele-
 graphie m. b. H., Berlin, Germany, a corpora-
 tion of Germany

Application September 13, 1933, Serial No. 689,171
 In Germany September 24, 1932

1 Claim. (Cl. 250—27.5)

The present invention relates to a discharge vessel or tube with a focussed electron ray pencil deflectible or deviable by electric, magnetic or combination fields.

5 The deflection of electron ray pencils in discharge tubes is accomplished by electric or magnetic means. In Braun or cathode ray tubes it is thus possible to register upon the luminous or fluorescent screen the curve shape of the deflecting impulses in rectangular coordinates if the directions of the two fields in projection upon the screen are at right angles to each other. Arrangements of this kind are not only used for oscillographic work, but also for television purposes.

20 However, the arrangements heretofore disclosed and used evidence a number of error sources, especially when the point is to cover comparatively long tracks upon the screen in a relatively short tube with relatively short ray pencils. If the ratio between the pencil or spot track upon the fluorescent screen to the pencil "leverage" (i. e. distance between the point of action or deflecting means and the screen) exceeds a certain limit, in 25 other words, if the angle of deflection becomes great in order that in commercially or technically useful tubes of reduced length, for instance, large television pictures may be re-created, defects in the pictures become very troublesome as experiments have demonstrated. These difficulties manifest themselves in the form of expansions or 30 spreading of the point or spot of impingement of the electron beam or pencil upon the screen whenever relatively large deflections are concerned. 35 This defect becomes especially annoying in high vacuum tubes though it arises also in the case of pencils focussed by a gas-filling with or without auxiliary electric or magnetic fields, though only to a limited degree.

40 These defects in re-creation of the picture are traceable to various causes. For instance, one cause resides in that the pencil leverages fail to be the same for different deflection angles and for the two deflecting means in both coordinates 45 in the arrangements usually employed. Ways and means have already been disclosed whereby, with a view to eliminating the said source of defects, the lengths of the pencil figured from the point of action of deflector means to the screen, 50 are rendered the same regardless of deflection. Another source of defects in picture re-creation for which the present invention discloses remedial ways and means follows from this consideration.

55 Referring now to the drawing, in which Fig. 1

shows a tube illustrating schematically the beam deflection paths;

Fig. 2 shows an optical analogue of an electron beam focusing system;

Fig. 3 shows one embodiment of my invention; 5 and

Fig. 4 shows another embodiment of my invention; a detailed description of my invention will follow.

Fig. 1 shows a usual arrangement wherein numeral 1 denotes the cathode surrounded by a Wehnelt cylinder 2, 3 is the anode, 4 a pair of deflector plates, and 5 the screen. Between anode and deflector plates there is mounted an annular coil 6 serving as an electron collector or condenser device, though the focussing action of the said coil could also be produced by suitable electrical fields. The pencil of electrons diverges considerably between the object to be imaged (here an anode being diaphragmic in nature) and the coil 20 the magnetic field of which is then so regulated and adjusted that the pencil will pass through the deflector means under convergent condition, and that, in non-deflected state, its node will come to be located upon the screen being of spherical form. If, however, the pencil is deflected it 25 will be impossible in an arrangement of the said sort to collect or condense the pencil-enclosing lines again in a point of sufficient sharpness whenever there occur large changes in direction, even 30 if the screen surface is so disposed that the pencil node will be caused to fall therein for all deflections. The more the convergent pencil is refracted by the deflecting field (the parabolic curving or bending of the pencil occasioned by the 35 electric field is disregarded in the drawing) the more will the size of its focus be altered compared with that of the non-deflected pencil.

The path of the electron pencil as shown in Fig. 1 could be likened to an optical ray path as 40 roughly indicated in Fig. 2. Inasmuch as the electrons are subject to constant acceleration, monochromatic light has been supposed to be dealt with in Fig. 2 which is subject to divergence between the slit 7 and the lens 8 whence it 45 traverses a prism 9 under convergent condition. Such an arrangement when turning the prism evidences a widening of the image of the slit in position II compared with position I. And in a very similar way the images of the diaphragm or 50 slit in a Braun tube show different diameters according to the position of the pencil.

The present invention discloses ways and means whereby, in spite of large angles of deflection, and in spite of considerable divergence and con- 55

vergence of the path of the ray pencil inside the high vacuum tube, but also in tubes having a gas-filling, the dimensions of the pencil image upon the screen are kept constant to a considerable degree for all directions or angles of deflection.

According to the invention, a focussing electric or magnetic system is disposed in the Braun tube for television and oscillographic purposes between 10 the deflector means, on the one hand, and the picture surface or screen, on the other hand. This arrangement is illustrated in Fig. 3. Hence, focussing by the device 6 is effected only after the deflection has been produced by means 4. 15 It is thus feasible to condense the lines of rays of the already deflected pencil in a sharp focus or node irrespective of the angle of deflection. This scheme is particularly valuable whenever the point is to re-create large pictures of uniform 20 sharpness with tubes of technically useful or acceptable length, if the pencil or spot, for instance, in the presence of a deflection a of over 20 mm. out of its position of rest, and of a length of pencil b of 320 mm. and less, is to 25 possess a constant diameter upon the screen, i. e., when the desideratum is to make the size of the picture independent to a large extent no matter what the changes in direction, in the presence of a ratio $a:b=20/320=1/16$ or deflection angles >3 degrees.

However, the conditions of picture re-creation become still more favorable if, according to Fig. 4, in addition to the condensing or focussing system 6a in the rear of the deflector means, a 30 focussing system 6b is disposed also between anode and deflector means. In that case, the condenser action of both focussing parts can be so adjusted that the electron pencil between the diaphragm acting, for instance, as the anode 35 as far as the first condensing system is divergent, is then rendered parallel and in this state caused to pass across the deflecting fields of an electrical or magnetic nature and is then, after deflection, re-focussed against by the second coil system. It will be, of course, suitable to so form 40 and design the focussing system interposed between deflecting device and picture surface that, optically speaking, it will act like a lens of very large aperture and yet sufficiently small focal length in order that the pencil, in spite of any 45 change in its sense of incidence, will be imaged with equal sharpness in all positions. In the construction of such an arrangement, this fact should also be kept in mind that the focussing 50 fields should not act into or trespass upon the spheres of action of the deflecting fields in order that, for instance, re-creation may occur in rectangular coordinates and that the corresponding form of the deflecting force-lines may be produced without any difficulties. If recourse is had 55 to annular coils for the purpose of insuring the

focussing between deflector system and screen, or between deflector system and anode then it will be suitable to make their distances from the deflector means not less than one-half of the coil diameter.

In the case of tubes which, for the purpose of concentrating the electron-ray pencil, are provided with a gaseous atmosphere, this focussing means will act upon the pencil even after the latter has undergone deflection. Having recourse again to the optical analogy it may be stated that the ionic core tending to focus the pencil will then have an effect as if, together with the deflecting forces, a focussing means of reduced aperture were partaking of the motion synchronously. However, even in tubes of this kind the disposition of a focussing device between deflector system and screen surface results in an improvement of the picture quality especially when the point is to modulate at the same time the intensity of the deflected pencil.

It might appear as if, as a result of the interposition of focussing means as disclosed and illustrated in Figs. 3 and 4 the Braun tube would turn out to be of greater length than the arrangements known in the earlier art as shown in Fig. 1. However, if the known arrangement is to produce pictures of like quality as in the arrangement of this invention, then in Fig. 1 the leverage (lever arm) of the pencil must be 30 greatly extended, for producing the same track of the spot upon the screen; in fact, the known arrangement must then be made of such elongated form that, no matter what the size of the picture, the ratio $a:b$ will be $=1/16$. But with the 35 new arrangement of this invention, satisfactory pictures also of larger picture area are realizable even with tubes that are technically more readily constructed.

Having now described my invention, what is 40 claimed is:

An electronic tube comprising means for developing an electron beam within the tube and for causing the developed beam to impinge upon a spherically shaped fluorescent end wall of the 45 tube, a pair of electrodes to which voltages are supplied to cause the developed beam to scan the entire active area of the fluorescent end wall of the tube upon which it impinges, a magnetic focusing coil intermediate the pair of electrodes 50 and the beam developing means, and a second magnetic coil intermediate the pair of electrodes and the fluorescent end wall for focusing the electrons of the beam to a sharply defined spot irrespective of the elemental area of the fluorescent 55 end wall upon which they are instantaneously impinging, said fluorescent end wall having a curvature concave toward the second magnetic coil and whose radius is the axial distance between the center of said coil and the fluorescent 60 end wall.

FRITZ MICHELSSEN.
